UNITED STATES PATENT OFFICE.

SINCLAIR STUART, OF PLAINFIELD, NEW JERSEY.

MEANS FOR REMOVING OIL FROM EXHAUST-STEAM.

SPECIFICATION forming part of Letters Patent No. 316,673, dated April 28, 1885.

Application filed February 24, 1885. (No model.)

To all whom it may concern:

Be it known that I, SINCLAIR STUART, of Plainfield, in the county of Union and State of New Jersey, have invented a new and useful Improvement in Means for Removing Oil from Exhaust-Steam, of which the following is a specification.

My invention is more particularly intended for steamships, but may be employed wherever surface-condensers are employed in connection with steam-engines.

It is a fact well recognized by steam-engineers that the oil or grease which escapes with the exhaust-steam from steam-engines produces great injury to surface-condensers and the pumps by which the water of condensation is taken therefrom and delivered into the boiler, and that it oftentimes produces rapid wear and shortens the life of the boilers.

The object of my invention is to provide an attachment which may be applied to steam-engines at small cost and by which all oil and grease will be caught or intercepted as they pass through the exhaust pipe or passage and separated from the steam and water of condensation, and, furthermore, to accomplish these desirable results without any loss of water of condensation, and without impairing the vacuum afforded by the condenser.

The means whereby these results are to be accomplished are shown in the accompanying drawings, and will be hereinafter described, and pointed out in the claims.

In the drawings, Figure 1 is a partly sectional elevation of a steam-engine and appurtenances embodying my invention. Fig. 2 is a sectional elevation, upon a larger scale, of a part of the main exhaust-pipe having my attachment arranged therein or applied thereto; and Fig. 3 is a sectional elevation on the plane of the dotted line $x-x$, Fig. 2.

Similar letters of reference designate corresponding parts in all the figures.

I shall only refer incidentally to the engine itself, as my invention does not involve any change therein beyond a slight alteration in the exhaust pipe or passage.

The engine herein shown comprises three cylinders, which may be of the compound variety, and which, with their steam chests and passages, are all formed in the cylinder structure A, which is supported on suitable fram-

ing. The crank-shaft B is mounted in suitable bearings in the framing, and with its cranks are connected the several connecting-rods not here shown.

C designates the main exhaust, through which passes all the steam which is exhausted from the engine. This exhaust pipe or passage C may be formed as part of the engine-framing, and in it a vacuum is maintained by the surface-condenser and pumps, which are of ordinary or any suitable construction.

In the exhaust pipe or passage C are placed any desired number of catch-plates or conductors, D. I have here shown four, which are arranged one above another and are inclined alternately toward opposite walls of the pipe or passage C. These plates or conductors may be made of sheet or cast metal, and are preferably formed with corrugated or channeled upper surfaces, forming series of gutters or channels, which run in the direction in which the plates or conductors are inclined. The plates or conductors are, as stated, arranged on opposite sides of the pipe or passage, and overlap each other at their inner and higher ends, so that no steam can pass down through the pipe or passage without being repeatedly deflected or turned aside by them. At the same time they do not impede the circuitous passage of steam through the pipe or passage, being arranged one above another.

The plates or deflectors D spring from or are attached at their lower ends to gutters or collectors a, from which pipes b b' deliver all oil or grease and any water which may be intercepted. The upper collectors or gutters a deliver their contents into the gutters below them by pipes b, and the pipes b' from the lower gutters unite and deliver the oil and grease with any water which may be intercepted through a pipe b' and into a receiver or chamber, E, external to the pipe or passage C.

The receiver or chamber E has at the bottom a pipe, c, leading to the lower part of the exhaust-passage C or to the condenser, and in which is a cock or valve, c'. It should also be provided with a water-gage, d, and with one or more cocks, e, (two being here shown,) for drawing off oil or grease. In the pipe b' is shown a cock or valve, b*, whereby the re-

ceiver or chamber E may be cut off from communication with the pipe or passage C, when desired.

In the ordinary operation of the apparatus 5 the valve b^* is open and the valve c' is closed. Oil and grease, with some water, will flow along the conductors and pipes and into the receiver E. When the glass gage d shows the receiver to be about full, or at any desired 10 time, the valve b^* is closed and the valve c' opened only long enough to permit the water of condensation, which will settle at the bottom, to flow therefrom until the water is below the lower cock e . That cock e is then 15 opened and oil drawn off. This oil, if pure, may be again used as a lubricant. When sufficient oil has been drawn off, the cock e is closed and the valve b^* opened to again allow the receiver E to fill with oil and water.

20 It will be observed that by my invention I separate and remove the oil and grease from the steam, and I accomplish this without any waste of water and without impairing the vacuum.

25 What I claim as my invention, and desire to secure by Letters Patent, is—

1. The combination, with the exhaust pipe or passage of a steam-engine, of catch-plates and conductors arranged therein for intercepting oil and grease and conducting it to the exterior of such pipe or passage, substantially 30 as herein described.

2. The combination, with the exhaust pipe or passage of a steam-engine, of inclined catch-plates D, arranged on opposite sides thereof alternately, collectors or gutters at the lower edges of such plates, and conductors or pipes leading therefrom to the exterior of the pipe or passage, substantially as and for the purpose herein described. 35

3. The combination, with the exhaust pipe or passage of a steam-engine, of catch-plates and conductors arranged therein for intercepting oil and grease and conducting it to the exterior of the pipe or passage, a receiver into 45 which the oil and grease with water are delivered, a pipe leading from the receiver to the exhaust or condenser and provided with a valve, and a cock for drawing oil from the receiver, substantially as herein described. 40

4. The combination, with the pipe or passage C and the receiver E, provided with a gage, d , and one or more of the cocks e , of the system of catch-plates D in the pipe or passage C, the pipe b' , delivering into the receiver, and the pipe and valve $c' c'$, for controlling the escape of water from the receiver, substantially as herein described. 50

SINCLAIR STUART.
